LARS ANDERSON, OF CHICAGO, ILLINOIS, ASSIGNOR OF ONE-THIRD TO HENRY S. MORTON, OF NEW YORK, N. Y., ONE-THIRD TO GEORGE W. STAHL, OF CHICAGO, ILLINOIS, AND ONE-THIRD TO TRIPLEX GAS ENGINE COMPANY, OF NEW YORK, N. Y., A CORPORATION OF NEW JERSEY.

PISTON-ROD CONNECTION.

No. 838,603.

Specification of Letters Patent.

Patented Dec. 18, 1906.

Application filed March 2, 1906. Serial No. 303,765.

To all whom it may concern:

Be it known that I, LARS ANDERSON, a citizen of the United States, residing at Chicago, in the county of Cook and State of Illinois, have invented certain new and useful Improvements in Piston-Rod Connections, of which the following is a full, clear, and exact specification.

This invention relates to improvements in piston-rod connections, and more particularly to the means for connecting the end of a piston-rod to its crank-shaft.

The object of the invention is to provide improved means for this purpose which will permit the rod to be quickly and efficiently connected to the crank.

A further object is to provide an improved simple and efficient means for tightening the connection, so as to compensate for and take up the wear of the boxes.

A further object is to provide improved simple and efficient means for securing the ends of a plurality of rods to the crank, and which means may be readily moved out of engagement with and out of the way of the ends of the rod, so as to permit the latter to be readily detached without removing the fastening means.

A further object is to provide an improved device of this character which will be simple in construction, cheap to manufacture, and effective in operation.

To the attainment of these ends and the accomplishment of other new and useful objects, as will appear, the invention consists in the features of novelty in the construction, combination, and arrangement of the several parts, as hereinafter more fully set forth and claimed, and shown in the accompanying drawings, illustrating an exemplification of the invention, and in which—

Figure 1 is an elevation, partly in section, of a crank and piston-rod connection constructed in accordance with the principles of this invention. Fig. 2 is a sectional view on line 2 2 of Fig. 1 looking in the direction of the arrows. Fig. 3 is a bottom plan view of the retaining-ring. Fig. 4 is an end elevation of the end of one of the piston-rods. Fig. 5 is a front elevation of Fig. 4.

In the form of the invention shown the crank-shaft is preferably comprised of sec-

tions 10 11, supported and journaled in suitable bearings, (not shown,) and keyed or otherwise secured to the adjacent ends of each of these sections is a disk or fly-wheel 12, and these disks or wheels are connected at a point remote from the center thereof by means of a suitable pin 13. This pin is preferably provided with reduced tapering extremities 14, forming shoulders 15. These reduced or tapering extremities 14 are adapted to enter suitable bearings 16 in the disks or wheels 12, with the shoulders 15 thereof preferably engaging a seat 17, and said pin is held from displacement by means of nuts 18, engaging the extremities thereof on the opposite side of the disks or wheels 12.

The pin 13 is provided with a longitudinal depression or recess 19, and the wheels or disks 12 are also provided with a groove or key-seat 20, which extends through the outer face thereof, and these grooves or recesses are adapted to register and receive a pin or key 21, whereby the disks or wheels 12 and the pin 13 are locked against independent movement with relation to each other.

The disks or wheels 12 are provided on their adjacent faces with a projecting interiorly-threaded rim 22, arranged eccentric to the shaft-sections 10 11 and surrounding the pin 13. If desired, the wheels 12 may be recessed, with the walls thereof provided with screw-threads, or an independent interiorly-threaded ring may be provided and secured to the faces of the wheels in any suitable manner. An interiorly-threaded sleeve or collar 23, provided with a lateral projecting circumferential flange 24, is adapted to enter the recess or stand within the projecting rim 22, with the flanged portion resting against the bottom of the recess or face 25 of the wheel 12. The external diameter of the flange or projecting portion 24 is somewhat less than the internal diameter of the recess or space formed by the rim 22. A ring 26 is provided with an interiorly-projecting portion 27, forming a shoulder 28, and said shoulder is of a height equal to the height or thickness of the flange 24 on the sleeve or collar 23. This ring 26 is adapted to rest against the face 25 of the wheel 12 and between the wall of the recess or inner face of the projection 22 and the periphery of the

flange 24, with the shoulder 28 thereof engaging the periphery of the flange and the projecting portion 27 extending over the face thereof, and said ring 26 is prevented from 5 independent rotation by means of suitable pins 29 passing through apertures 30 therein and into the wheel 12, as will be understood. If desired, this ring may also be provided with peripheral threads to engage the threads 10 on the member or rim 22.

A lock-nut or ring 31, provided with peripheral threads, is adapted to engage the threads on the wall of the recess or projecting rim 22 above the ring 26 for preventing the 15 latter from becoming displaced, and said ring 31 is provided with suitable apertures or depressions 32, adapted to receive the ends of a spanner-wrench, whereby the said ring may be adjusted as desired. It will thus be 20 seen that the sleeve or collar 23 has a loose or swivel connection with the disk or wheel 12 and may be rotated in any suitable manner, preferably by means of a suitable wrench engaging apertures 33 therein or by means of 25 the fingers gripping a milled or roughened portion 34 of its periphery.

A suitable sleeve or collar 35 surrounds the bearing 16 and is of a diameter slightly less than the internal diameter of the sleeve or 30 collar 23, and said latter sleeve or collar 35 is provided with peripheral threads adapted to engage the internal threads of the sleeve or collar 23. The lower portion of the sleeve or collar 35 is provided with a notch or recess 35 adapted to coöperate with a corresponding groove or recess in the bearing 16, and a key 36 is adapted to be seated in the coöoperating grooves, and said key serves to permit the collar or sleeve 35 to have a longitudinal movement 40 with relation to the bearing 16 and the sleeve or collar 23 and yet prevent a rotary movement of said sleeve or collar 35 with respect to the bearing 16. Thus when the sleeve or collar 35 is rotated the sleeve or collar 35 will be drawn back longitudinally on the bearing 16, and the height of the collar 23 is such that the collar 35 will recede and stand within the sleeve or collar 23.

The interior of the upper portion of the 50 sleeve or collar 35 is enlarged or flared, forming a circumferential interior inclined wall or face 37.

The ends of the bearings 16 preferably project slightly beyond the shoulders 15 of the 55 pin 13 for a purpose to be set forth.

Any number of piston-rods 38 and pistons 60 may be employed in connection with this invention, but in this exemplification there are illustrated three, and each of these rods is provided at its end adjacent the crank-pin 13 with a section of a box 39, which sections 65 extend around the crank-pin 13, and each box is of such a size that when assembled there will be a space between the adjacent faces, so as to permit an oscillation with reference to

each other as the crank-pin rotates. These boxes are constructed on an arc in cross-section, but are conical or tapered longitudinally from a point adjacent the center toward their ends, as at 40. These extremities 70 taper to a diameter smaller than the diameter of the flaring or conical opening in the end of the sleeve or collar 35, and each of the boxes 75 are of a length to permit the same to engage the crank-pin 13 and with its extremities between and in close proximity to the ends of the bearings 16, thereby preventing lateral displacement of the boxes. To the opposite ends of these rods are connected piston-heads which move in the cylinders 41. 80

Assuming the parts to be assembled and in position as shown in Fig. 1, should the boxes 39 become worn all that is necessary is to turn the sleeve or collar 23, which will force the collar or sleeve 35 outward and the 85 incline face or wall 37 farther up the incline portion 40 of the boxes, which will tighten the boxes against the shaft. When it is desired to detach the rods, the collar 23 is rotated in an opposite direction, causing the 90 collar or sleeve 35 to be drawn back out of engagement with the boxes 39 and into the sleeve or collar 23, so that the extremity of said collar 35 will clear the end of the boxes, thereby permitting the piston-rods to be 95 readily removed.

It is to be understood that it is not desired to be limited to the exact details of construction or arrangement of the several parts, as numerous changes may be made without departing from the spirit of the invention. 100

What is claimed as new is—

1. In a device of the class described, the combination of a crank and crank-pin, a piston-rod, a segmental box member thereon 105 adapted to engage the pin, a collar rotatably mounted on the crank and surrounding the pin, and means surrounding the pin and member for securing the latter in position, said means being connected to and adjustable by the collar in a longitudinal direction with relation to the pin.

2. In a device of the class described, the combination of a crank and crank-pin, a piston-rod, a segmental box member thereon 115 adapted to engage the pin, a collar swiveled to the crank and surrounding the pin, means surrounding the pin and member for securing the latter in position, said means being connected to and adjustable by the collar, and means for preventing a rotary movement of the securing means.

3. In a device of the class described, the combination of a crank, a crank-pin, a collar 125 swiveled to the crank and surrounding the pin, a second collar surrounding the pin, means for preventing rotary movement of the second collar, a piston-rod, a segmental box member thereon adapted to engage the pin, and a connection between the two col- 130

lars, whereby the rotation of the outer collar will cause the inner collar to move into engagement with and surround the box member for securing the latter in position.

5 4. In a device of the class described, the combination of a crank, a crank-pin, a collar surrounding the pin, means engaging the collar for rotatably supporting the same on the crank, a second collar screwed to and standing 10 within the first collar, a piston-rod, a segmental box member thereon adapted to engage the pin, and means whereby the rotation of the outside collar will force the second collar out of said first collar and cause the 15 same to engage and surround the box member.

5 5. In a device of the class described, the combination of a crank, a crank-pin, a piston-rod, a segmental box member thereon adapted 20 to engage the pin, interengaging collars surrounding the pin, one of said collars being provided with a peripheral flange, a shouldered ring secured to the crank and loosely 25 engaging the flange, and means engaging the outer collar for causing said last-named collar to advance and surround the box member when the first collar is rotated.

6 6. In a device of the class described, the combination of a crank, a crank-pin, a piston-rod, a segmental box member thereon adapted 30 to engage the pin, and provided with tapering extremities, interengaging collars surrounding the pin, means for rotatably securing one of the collars to the crank, the other collar being 35 provided with a conical seat, and means engaging said other collar, whereby said collar will be advanced when the first collar is rotated to cause the conical seat to surround and engage the tapering extremity of the box 40 member.

7 7. In a device of the class described, the combination of a crank, a crank-pin, a piston-rod, a segmental box member thereon adapted 45 to engage the pin, interengaging collars, one of said collars surrounding and engaging the box member, means for rotatably supporting the other collar, and means whereby the first collar will be caused to move into the second collar and out of engagement with the box member when said 50 second collar is rotated.

8. In a device of the class described, the

combination of a crank, a crank-pin, a piston, a segmental box member thereon adapted to engage the pin, and provided with tapering extremities, interengaging collars surrounding the pin, means for swiveling one of the collars to the crank, the other collar being provided with a conical seat adapted to surround and engage the extremities of the 60 box member, and means for causing the second collar to move through the first collar when said first collar is rotated.

9. In a device of the class described, the combination of a crank, a crank-pin, a piston-rod, a segmental box member thereon adapted to engage the pin, interengaging collars surrounding the pin, one of said collars being adapted to engage the box member, the other collar being provided with a peripheral flange, a ring engaging the flange and the crank, means for preventing rotation, and means for preventing displacement of the ring, and means for preventing rotation of the first collar, whereby said collar will 75 be moved with respect to the second collar when said second collar is rotated.

10. In a device of the class described, the combination of a crank, a crank-pin, said crank being provided with a screw-threaded 80 recess surrounding the pin, interengaging collars surrounding the pin, one of said collars being provided with a peripheral flange, said flange being of less diameter than the diameter of the recess, a ring within the recess, resting upon the flange, and provided with a shouldered portion between the periphery of the flange and the wall of the recess, a peripherally-threaded ring engaging the threads of the recess and resting against the 85 first ring to prevent displacement thereof, said other collar being adapted to engage and surround the box member, and means for preventing rotation of the second collar, whereby said second collar will be advanced 90 or retracted when the first collar is rotated.

In testimony whereof I have signed my name to this specification, in the presence of two subscribing witnesses, on this 28th day of February, A. D. 1906.

LARS ANDERSON.
